2 Claims. (Cl. 179—171)

1

This invention relates to automatic amplitude control for electrical currents and voltages and more particularly to automatic volume or amplitude controls for electrical amplifiers such as are commonly used in connection with seismic surveying.

A common method of automatically controlling amplitude in seismograph amplifiers, and volume in radio amplifiers, consists in rectifying a portion of the amplified signal current, using this rectified current to develop a potential across a resistance, and applying this potential through suitable filtering, as a bias to one or more amplifier tubes.

This method has several disadvantages. First, it is difficult by this method to obtain a large enough change in grid bias for a given change in signal to effect a very close control of amplitude. Ordinarily the control will be close enough for radio amplifiers, but not close enough for scientific measuring devices such as seismograph amplifiers. Second, there is a tendency to feed back the fundamental signal frequencies into the grids of the preceding amplifier tubes thereby causing regeneration, degeneration, or distortion, depending upon the phase relationship.

It is the purpose of this invention to provide an automatic amplitude control for electrical currents and voltages, that avoids these difficulties and is particularly adapted to the controlling of seismograph amplifiers, but is adaptable to use in numerous other circuits in which generally similar control is desirable.

Broadly stated, the present invention comprises varying the conductance of a thermionic tube by varying its cathode heating current in accordance with the amplitude of the voltage or current to be controlled and using this variation in conductance to effect the control.

If the plate current of a thermionic tube is plotted graphically against its filament or heater current, it will be found that as the heater current is increased, the plate current rises, at first very slowly, then with extreme rapidity and thereafter very slowly again until sufficient current is passed through the filament or heater to cause it to burn out. The control contemplated by this invention may be accomplished by operating the thermionic control tube about either the upper or lower bend of its filament current-plate current characteristic curve, or on the steep portion of the curve.

The thermionic control tube may be of practically any type, but diodes having directly heated cathodes of relatively low current rating are gen-

2

erally preferred. Triodes, tetrodes, pentodes, etc., may be used, and dual purpose tubes may also be used, but generally are unnecessary. Indirectly heated cathodes may also be used in some instances but generally are too slow in their response to changes in heater current to be effective.

In general, the filament of the control tube may be heated either directly or indirectly by all or part of the signal current from the amplifier or by all or part of the current that is to be controlled. Since the control tube acts as a full wave rectifier, with respect to the filament current, it automatically eliminates the fundamental frequency of the signal current from its plate current and the temperature lag in the filament generally tends to eliminate all except very low frequencies.

A plate circuit return for the control tube may be taken from one side of the filament or the filament may be bridged by resistance and the plate return attached to a center tap on that resistance to further avoid introducing signal current components into the plate circuit of the control tube. Alternatively, the filament itself may be provided with a center tap for the plate return or the transformer driving the filament may be center tapped.

When the current to be controlled is of a sufficiently high frequency, the filament current of the control tube may be fed to the control tube through condensers to isolate the control tube circuit from the source of the current or voltage to be controlled insofar as direct current is concerned. Alternatively, the filament current may be supplied through a transformer for the same purpose.

The control tube is now a variable resistance having a wide variation in resistance in response to moderate changes in filament current. Furthermore, this variation in resistance does not occur linearly with respect to changes in filament current and this fact makes the variable resistance of the control tube particularly useful as a means to control electrical currents or voltages.

In order to use the variable resistance of the control tube for the purpose of controlling currents or voltages, it is necessary that a D. C. plate voltage be applied, in the proper direction, between the filament and plate of the control tube. Thus, the control tube may be connected into a capacitance-resistance coupled voltage amplifier tube as a part of the load resistance and the usual plate supply voltage of the amplifier

tube will be partly applied across it. Then as the signal level increases and the filament current is thereby increased in the control tube, the load resistance furnished by the control tube will drop sharply, thus reducing the voltage amplification and controlling the amplitude of the output signal.

Since the resistance across a diode is practically infinite when the cathode is cold, it is desirable in such circuits to place a high resistance between the cathode and plate of the control tube so that plate voltage will be applied to the amplifier tube when the circuit is first energized and until sufficient signal current flows in the filament of the control tube to lower its resistance to a point where a voltage can be applied through it to the plate of the amplifier tube. Alternatively, the circuit can be such that sufficient current will flow through the filament of the control tube even under no-signal conditions, to lower the resistance of the control tube to some finite value that will permit voltage to be applied through it to the plate of the amplifier tube.

In other instances, it may be desired to use the control tube to control either the grid bias of one or more amplifier tubes or the attenuation of an attenuating network. By appropriate circuit arrangements the control tube can be caused to accomplish either of these purposes or to exercise its control in any other manner in which a variable resistance could be used to control the current or voltage in a circuit. The only special problem involved is that of applying the necessary direct current plate voltage to the control tube.

No attempt will be made here to detail all of the methods by which the control tube may be caused to control particular currents and voltages but an example of the preferred use of the control tube to control a practical seismograph amplifier will be illustrated and a few additional examples will be given of the exercise of the control tube functions by the control of grid bias, plate load, and attenuation of attenuating circuits.

For further details and a more complete understanding of the principles and preferred methods of applying the principles of this invention, reference may be had to the appended drawings and the following detailed description thereof.

In the drawings:

Figure 1 is a schematic illustration of one method of applying the principles of this invention to the control of an amplifier, in such a way that the control tube controls the grid bias of one or more tubes of an amplifier;

Figure 2 is a schematic illustration of a method of applying the principles of this invention so that a control tube controls the operation of an amplifier by controlling the plate load of one of the tubes of an amplifier;

Figure 3 is a schematic illustration of another method of applying the principles of this invention so that the control tube controls the degree of attenuation effected by an attenuating network; and

Figure 4 is an illustration of the use of the principles of this invention to control the operation of a seismograph amplifier.

As is illustrated in Figure 1, the principles of this invention have been applied to the control of a typical resistance-capacity coupled voltage amplifier stage. The input to this stage is applied between a B- connection 13 and a grid connection 11 in the usual way with a condenser 12

located in the grid connection to block direct current. From the blocking condenser 12 connection is made directly to the control grid 13 of a conventional triode amplifier tube 14 of the indirectly heated cathode type. Obviously, a directly heated cathode type of tube, a tetrode, pentode or other special type of tube could be used in place of the triode 14 that has been illustrated.

The cathode 15 of the amplifier tube is shown as connected through a resistor 16 and a condenser 17 to the B- line 10 and these parts serve to provide a normal grid bias through a resistor 18 one end of which is connected to the B- line 10 and the other end of which is connected by resistance 19 to the grid 13. The plate circuit of this tube is conventional, the plate 20 being connected through a resistor 21 and a B- battery 22 which furnishes plate potential, to the B- line 10. A condenser 23 is shunted across the B- battery 22 in accordance with common practice. The plate 20 is connected to the grid of the next amplifier tube or to the detector or other device to which the amplifier signal is to be supplied, through a blocking condenser 24 in the usual manner. Thus far we have a conventional voltage amplifier circuit of the resistance-capacitance coupled type.

In order to apply the principles of this invention to the circuit thus far described, the filament 25 of a diode tube 26 is connected between the B- line 10 and a source of control current (not shown). Ordinarily, this source of control current will be the ungrounded side of the output of the amplifier or the output of some stage of the amplifier. Quite often the output will exist between the B- line and some other point in the circuit from which it can be taken directly, but if not it can be applied between the B- line 10 and the filament lead 27 of the diode 26 through the medium of a transformer or condensers. Whatever attenuation is found to be necessary can be placed in the filament lead 27 to reduce the current flow therethrough to the amount required to operate the diode 26 at the desired point in its characteristic curve.

The plate 28 of the diode 26 is then connected through a source of voltage such as a battery 29 to the resistance 19 which connects to the grid of the amplifier triode 14. With this circuit arrangement, as long as the filament 25 of the diode 26 is cold, the circuit which includes the diode and the battery 29 will be open and no current will flow through this circuit and hence through the resistor 18. Therefore, no voltage will be developed across this resistor. As the filament 25 of the diode is heated an increasing amount of current will pass through the diode 26 and through the resistance 18 thus developing an increasing potential across this resistance. By reason of the fact that the negative terminal of the battery is connected to the grid end of the resistor 18 this voltage will be negative and will tend to reduce the amplification of the triode 14, thus reducing the overall amplification of the amplifier until the current to the filament 25 of the diode 26 is reduced, which in turn reduces the current through the resistor 18 and reduces the negative bias on the grid 13 of the triode 14. By arranging the circuit to operate the diode 26 at the lower bend of its characteristic curve or on the steep portion of its characteristic curve, a very exact control can easily be achieved. By reason of the filtering accomplished by the diode 26, the fundamental frequency of a control sig-

nal will not be fed back into the grid circuit of the amplifier tube and by reason of the temperature lag of the filament there is little tendency to feed back any except very low frequencies into the grid of the amplifier tube 14. Thus relatively little or no filtering is required between the output of the amplifier and the filament of the diode 26.

In Figure 2 there is illustrated an application of the principles of this invention to the control of an amplifier of the same general type, by changing the plate load of the voltage amplifier tube involved. Again, the input is to the B-line 10 and a grid lead 11 which contains a blocking condenser 12. In this case, however, the grid is also connected directly to the B-line through a grid resistor 30. Normal bias is again provided by connecting the cathode 15 to the B-line through a resistor 16 and a condenser 17. The plate 20 of the triode 14 is again connected through a resistor 21 and a B battery 22 to the B-line 10 and this battery is again shunted by a condenser 23, all as before. Again the plate is connected through a blocking condenser 24 to the grid of the next amplifier tube.

In the arrangement shown in Figure 2, however, control of the voltage amplification of the amplifier tube is provided by connecting a diode tube 31 across the plate resistor 21. In order that the source of plate voltage, the battery 22, also supply plate voltage for the diode, plate 32 of the diode is connected to the battery end of the plate resistor 21, that is to a point between the resistor 21 and the positive terminal of the battery 22. The filament 33 of the diode 31 is then connected to the opposite end of the resistor 21. In order to isolate the plate circuit of the triode 14 from the source of control current, control current is supplied to the filament 33 of the diode 31 through a transformer 34. By using a center tapped filament 33 in the diode 31 and connecting the center tap to the plate lead of the triode 14 and supplying current to the two outer leads of the filament 33 from the transformer 34, the feeding of signal currents into the plate circuit of the amplifier tube is avoided.

The result of this circuit is the shunting of the plate resistor 21 by the diode 31. As the signal current at some selected stage in the amplifier becomes excessive, a sufficient amount of that signal current is fed back into the filament 33 of the diode 31 to cause that diode to become conductive. This shunts the plate resistor 21 greatly reducing its effective resistance and hence reducing the plate load on the triode 14 and thereby reducing the voltage amplification of this stage of the amplifier.

Still another embodiment of this invention is illustrated in Figure 3 in which the principles of this invention are applied to control the attenuation of an attenuating circuit. The attenuating circuit receives its input current through two leads 40 and 41 and supplies current, attenuated to the desired extent through leads 42 and 43. In this circuit lead 40 is connected to lead 42 through a resistance 44, and lead 41 is connected to lead 43 through a resistance 45. A shunting resistor 46 is then connected between leads 41 and 42 and another shunting resistor 47 is connected between lead 40 and lead 43. If resistances 44, 45, 46 and 47 are properly related, a balanced bridge will result with infinite attenuation between points 40 and 41 and points 42 and 43.

Changing the effective resistance of one of

the resistors in this attenuating network, such for example as the resistance of the resistor 45, will vary the attenuation over a wide range without otherwise greatly affecting the characteristics 5 of the circuit.

It would be difficult to change the resistance of the resistor 45 by shunting it with a single control diode and, therefore, a dual diode has been used in this embodiment. This dual diode 50 contains a single filament 51 and two plates 52 and 53. By connecting one of these plates to each end of the resistor 45 and supplying plate voltage to a mid point on the resistor 45 from a source of plate supply such as battery 54, the 10 ends of the resistor 45 may be maintained at the same potential and yet the two halves of the diode effectively shunted across the resistor 45. The filament of the diode 50 may either be made with a center tap return or may be bridged, as 15 shown in the drawing, by a resistor 55 or driven by a center-tapped transformer, so that the B-battery return may be connected to a central point. Thus the possibility of introducing signal 20 currents into the attenuating network may be lessened. As before the signal currents which 25 are to control the attenuation are applied to the filament of the diode, in this case through leads 56 and 57.

In Figure 4, there is illustrated a rather complete 30 arrangement for the use of the principles of this invention in the seismograph amplifier circuit. In this circuit, electrical signals generated by a seismometer in the course of making a seismic survey are introduced into the primary of a transformer 60 through leads 61 and 62. The opposite ends of the secondary of this 35 transformer are connected to the control grids of two remote cut off pentodes 63 and 64 connected as triodes so that these tubes will act in 40 push-pull to amplify the signals. A grid return line 65 is connected to a center tap on the secondary of the transformer 60.

A "varistor" 66, which is a non-linear resistance with strong limiting action, is connected 45 between the two control grids of the two tubes 63 and 64 to provide a preset amount of signal "limiting" of the incoming signals.

The cathodes of the tubes 63 and 64 are connected 50 through a conventional cathode resistor 67 to a cathode return line 68 which connects to the plate supply and receives a voltage that is negative with respect to the plate voltages of the 55 amplifier tubes but positive with respect to ground. This plate supply is not shown but two terminals 69 and 70 are shown and an appropriate 60 source of voltage is to be connected thereto. Usually the 90 volt terminal of the plate supply will be attached to terminal 69 and the 180 volt terminal of plate supply attached to terminal 70. The negative terminal will then be connected to ground. A second pair of tubes, 65 constituting a second stage of amplification may be similarly connected for control.

In the two tubes 63 and 64, the screen grids 65 of the variable mu or remote cut off pentodes are used as plates and are supplied with plate voltage through plate load resistors 71 and 72, respectively. The suppressor grids and plates of these tubes are not used for amplification, but 70 grounded for shielding. The result is a push-pull remote cut off triode stage. This is not an essential part of this invention.

Signal currents from the two tubes 63 and 64 are introduced into the primary of a coupling 75 transformer 73 which is connected between the

screen grids (acting as plates) of the two pentode tubes in series with a blocking condenser 74.

From the secondary of the coupling transformer 73, the amplified signal currents are again impressed upon the control grids of another pair of pentode tubes connected exactly as are the first pair of pentode tubes and again the signal output is introduced into a coupling transformer 15. As illustrated, the amplification of the second pair of tubes is also controlled. From the coupling transformer 15 the signals are introduced into a conventional amplifier and the output of this amplifier is carried by connections 76 and 77 to a conventional recording galvanometer.

Control of the amplification of this circuit is provided by a relay and a control circuit. The relay receives actuating power through connections 78 and 79 from the direct current output of the amplifier. Thus when the first seismic waves pass through the amplifier, current is caused to flow in lines 78 and 79. These lines 78 and 79 are connected to a relay 80 which operates to open a switch 81 thus actuating the control circuit in a manner that will now be described.

When closed, the switch 81 serves to connect the grid return lines for the two pairs of amplifier tubes to the center tap of a potentiometer 82. One end of this potentiometer is grounded. The other end is connected to the cathode return line 68 and this line is normally maintained about 90 volts above ground potential so there is a potential drop of around 90 volts across the potentiometer 82. By appropriate adjustment of the slider of the potentiometer 82, any desired potential may thus be placed on the grids of the four tubes involved, from the potential of the cathodes of these tubes to a potential around 90 volts below, or negative, with respect to the cathodes.

Normally, the potentiometer will be set so that prior to the opening of the switch 81, the potentials on the grids will be such that the first incoming signals will be amplified to approximately the desired extent. As soon as the first incoming signals arrive and are amplified, the relay 80 will be actuated to open the switch 81 and the potential of the grids of the four tubes will thereafter depend upon potential across a condenser 89 which is connected between the grid return line 65 and the cathode return line 68.

As long as this condenser 89 retains its original charge the relative potential of the grids will remain the same as it was before the switch 81 was opened. However, a discharge path to the cathode return line is provided through a resistor 83 connected in series with a vacuum tube 84 and a second resistor 85. The vacuum tube 84 has its filament connected to the resistor 83 which in turn is connected to the grid return line 65 and has its plate connected to the resistor 85 which in turn is connected to the cathode return line 68. This provides a path through which the negative charge on the grids of the pentode tubes can be dissipated and the grids reach the same potentials as the cathodes. However, a control tube 86 is connected between the plate of the discharge tube 84 and ground so as to control the rate at which the negative potential is reduced. Filament current for the discharge tube 84 is provided by battery 87 through a resistor 88 which regulates the amount thereof. Filament current for the control tube 86 is pro-

vided from the output of the amplifier by means of a connection 90 and ground connections.

The operation of the control tube 86 results from the fact that the current passing through this tube must also pass through the resistor 85 and the fact that the greater the current is that passes through resistor 85, the greater is the potential drop across it. Thus as long as the filament of the control tube 86 is heated to a relatively high degree and the resistance of the control tube 86 is relatively low, the potential drop across the resistor 85 will be relatively high and the potential of the plate of the discharge tube 84 will be relatively slight with reference to ground. Thus the current flow through this tube will be zero or some very small amount and the potential of the grids of the four tubes will not be reduced or at least will not be reduced rapidly while the control tube 86 is conductive. As the output of the amplifier falls due to the reception of weaker signals, the filament of control tube 86 will be heated to a less extent; the resistance of this tube will increase; the current flow through this tube and through resistor 85 will decrease; the potential drop across resistor 85 will decrease; and the potential on the plate of the discharge tube 84 will increase thus increasing the current flow therethrough and consequently decreasing the negative bias on the grids of the four pentode tubes. This in turn will increase the amplification of the four pentode tubes and raise the output of the amplifier until the filament of the control tube 86 is again heated to such an extent that the current flow through it and hence the potential drop across the resistor 85 will have increased sufficiently to stop, or at least substantially stop, the flow of current through the discharge tube 84 and hence the discharging of the condenser 89 which supplies the bias to the grids of the tubes. This cycle of operations will continue during the reception of a whole series of seismic wave signals and will tend to stabilize and control the amplification at a desired level during the reception of the whole series of seismic waves despite the fact that they are generally of progressively decreasing amplitude. Obviously, since the discharge tube 84 acts as a rectifier, the grid bias can never be increased except by closing the relay switch 81.

Both the discharge tube 84 and the control tube 86 have been shown in the drawing as tetrodes because this type was used in the original work on this amplifier. However, diodes, triodes, tetrodes, pentodes or multi-functional tubes could be used in their stead. Similarly, other types of tubes than pentodes could be used in the push-pull amplification stages.

It is to be understood that suitable attenuation will be provided in the circuits leading from the amplifier to the relay and from the amplifier to the control tube 86 to cause these parts of the circuit to operate in the desired manner and to prevent undue dissipation of the signal into these circuits. Many other modifications and many other changes in details may obviously be made within the scope of this invention.

What is claimed is:

1. An automatic volume-controlled amplifier that comprises a pair of thermionic tubes connected in push-pull relationship, means to supply the plates of said thermionic amplifier tubes with a potential positive with respect to the cathodes, a common grid return for the control grids of

said two thermionic tubes said common grid return connecting to said cathodes through a condenser, a resistor connected at one end to said cathodes, means to supply the opposite end of said resistor with a potential negative with respect to said cathodes, a variable contact on said resistance, a magnetically-operated switch for connecting said variable contact to said grid return, connections connecting said magnetic switch to the output of said amplifier so that said magnetic switch will be opened upon the passing of the first signals through the amplifier and will thereafter remain open, a thermionic control tube having its cathode connected to the negative end of the above-mentioned resistor and having its plate connected through a second resistor to said cathodes, connections between the heating element of said control tube and the output of said amplifier for heating said heating element in accordance with the output of said amplifier, and a rectifier and resistance connected in series between the plate of said control tube and said grid return for permitting the discharge of the above-mentioned condenser under the control of said control tube. 25

2. In an amplifier circuit that comprises at least one thermionic tube amplifier, connections for applying signals to be amplified between the grid and the cathode thereof, means for supplying operating grid bias to the grid, a plate load, 30 means for taking amplified signals from the plate

circuit and means for applying operating plate voltage between the plate and cathode, the improvement that comprises an automatic volume control for said circuit, including a thermionic control tube, connections between the output circuit of the amplifier and the heating element of the control tube for supplying a heating current to the heating element proportional to the output of the amplifier, and connections connecting 5 the plate circuit of the control tube into the grid circuit of the amplifier tube, said connections consisting of a resistance connected into the grid circuit of the amplifier tube and further connections connecting the plate circuit of the control tube in series with a source of voltage and across said resistor, the control tube and source of voltage being so connected as to apply negative voltage to the grid when the control tube is conductive, so that increases in the output 10 of the amplifier decrease the resistance through the control tube and lower the potential of the grid of the amplifier tube and thus reduce the amplification of the amplifier tube.
